UNITED STATES PATENT OFFICE.

ALEXANDRE COLLARD, OF COURNUS, FRANCE, ASSIGNOR TO THE SOCIETE: MANUFACTURE METALLURGIQUE DE COURNUS, OF COURNUS, FRANCE.

HANDLE FOR SAUCEPANS AND OTHER VESSELS.

1,403,232.

Specification of Letters Patent. Patented Jan. 10, 1922.

Application filed May 4, 1920. Serial No. 373,721.

To all whom it may concern:

Be it known that I, ALEXANDRE COLLARD, a citizen of the French Republic, residing at Cournus, in the Department of Saône-et-

5 Loire and Republic of France, have invented certain new and useful Improvements in Handles for Saucepans and other Vessels, of which the following is a specification.

This invention consists in improvements in 10 the construction and mounting of handles, insulating or non-insulating, for saucepans and other vessels.

This invention relates more particularly to the known types of handle, insulating and 15 non-insulating, consisting of a tang fixed in an attaching member that is made in one piece with or fixed to the vessel, this tang being adapted to receive a sheath mounted in such a manner as to be insulating or non-insulating, and fixed by means of a cap and 20 shackle fixed to the end of the tang.

The above described type of handle has certain drawbacks, mainly inherent to the manner of fixing the tang in the attaching 25 member, such as for instance by screwing by simple driving, or other means, and also to the fact that by reason of shocks, successive expansions and other causes, the sheath consisting of a metal or other casing or 30 shell, becomes loose and liable to turn, thus entailing possible accidents and difficult or even impossible repairs, since all the parts constituting the handle form a fixed combination with the vessel.

35 The improvements of the present invention are designed to obviate the above stated drawbacks.

The present invention is illustrated by way 40 of example in the accompanying drawings in which:—

Fig. 1 is a section of a handle in its assembled state.

Fig. 2 is a similar view of the handle showing however its parts separate from one 45 another.

According to this invention, the tang 1 is fixed in the attaching member or lug 2 of the vessel in such a manner as to be unable to become detached therefrom or to turn on its 50 own axis. With this object, its end which is fixed by casting in the metal of the lug 2, is up-set as shown at 3, and is formed with a number of barbs 4 which oppose its withdrawal from the lug 2.

55 Upon this tang 1 there is slipped a shell 5

of metal or other material which may be mounted in an insulated manner in the socket 6 of the lug 2 by means of a ring 7 of heat-insulating or other material.

The fixing of the shell 5 is effected in this 60 construction by means of a nut 8 comprising a screw-threaded sleeve 9 arranged above and extending through the usual cap 10 that closes the shell 5. This sleeved-nut engages the screw-threaded end of the tang 1, thereby assuring a tight joint, and enabling the shell 5 to be tightened up at will in use. Above the nut 8 there is mounted on a sort of small sleeve 11 fixed to the nut 8, shackle 12 that is held in place by a screw 13 which 70 allows it to turn freely, so that it can always adjust itself in the axis of the utensil and will thus allow the latter to be hooked on to the pot board, which could not be possible if the said shackle were fixed to the nut 8 75 which latter must be necessarily tightened up by hand or otherwise from time to time in order to take up any looseness in the fit of the shell.

The improvements also allow of a rapid 80 and easy dismounting and remounting of the handle, thereby rendering it possible to change at will the shell on the insulating socket or any other constituent part of the handle.

It is to be understood that modifications as regards the details, and also other improvements may be made in the improved handle without departing from the nature of the invention.

Having now particularly described and ascertained the nature of my said invention and in what manner the same is to be performed, I declare that what I claim is:

1. A vessel having a short integral lug 95 extending outwardly from one side wall, a tang with one end extending into and cast into said lug, a handle shell surrounding the projecting portion of the tang, means on the end of the lug against which the adjacent 100 end of the shell abuts for holding the shell in spaced relation to the tang, a button upon the end of the tang and abutting the outer end of the shell to space it from the tang, a swivel ring device threaded upon the end of 105 the tang for clamping the button and shell tightly against the said means, and for permitting the vessel and handle to swing freely when suspended by the ring device.

2. A vessel having a short integral lug ex- 110

- tending outwardly from one side wall, a tang extending from said lug, a handle shell surrounding the projecting portion of the tang, an annular button of heat insulating material interposed between the end of the shell and lug for insulating the shell from the lug and tang and holding the shell in spaced relation to the tang, and means adjustably carried by the outer end of the tang for spacing the outer end of the shell from the tang and clamping the shell tightly against the annular button and lug.
3. A vessel having a short integral lug extending outwardly from one side wall, a tang 15 extending from said lug, a handle shell surrounding the projecting portion of the tang, an annular button of heat insulating material interposed between the end of the shell and lug for insulating the shell from the lug 20 and tang and holding the shell in spaced relation to the tang, a spacing button abutting the outer end of the shell, and a nut threaded upon the free end of the tang and abutting the spacing button for spacing the outer 25 end of the shell from the handle and for clamping the shell and both of the buttons tightly together and against the lug.
4. A vessel having a short lug on one side wall, and a cavity in the end of the lug, a heat insulating button disposed in the cavity, 30 a handle shell having one end disposed in said button, a button abutting the other end of the shell, and means including an element passing through the shell and into the lug
- for clamping the shell between the buttons 35 and to the lug in spaced relation to the element.
5. A vessel having a short integral lug extending outwardly from one side wall, a tang extending from said lug, a handle shell 40 surrounding the projecting portion of the tang, an annular button of heat insulating material interposed between the end of the shell and lug for insulating the shell from the lug and tang and holding the shell in 45 spaced relation to the tang, a button for spacing the outer end of the shell from the tang, and a swivel ring device having an adjustable connection with the tang for clamping the shell between the buttons and against 50 the lug and permitting the vessel to swing freely when suspended thereby.
6. A vessel having a short integral lug extending outwardly from one side wall, a tang 55 extending from said lug, a handle shell surrounding the projecting portion of the tang, and a swivel ring device adjustably connected to the outer end of the tang for clamping the shell in place upon the tang and supporting the vessel to swing freely 60 when suspended thereby.

In testimony whereof I affix my signature in presence of two witnesses.

ALEXANDRE COLLARD.
